INVENTOR

UNITED STATES PATENT OFFICE

162,953

KNITTED SLIPOVER ADJUSTABLE NECKLINE BLOUSE

Josephine Hayward, New York, N. Y., assignor to
Whitesons, Inc., New York, N. Y.

Application April 21, 1950, Serial No. 9,378

Term of patent 7 years

(Cl. D3—25)

To all whom it may concern:

Be it known that I, Josephine Hayward, a citizen of no country, residing in New York city, county of New York, and State of New York, have invented a new, original, and ornamental Design for a Knitted Slipover Adjustable Neckline Blouse, of which the following is a specification, reference being had to the accompanying drawing, forming part thereof, wherein,

Figure 1 is a front elevational view of a knitted slipover adjustable neckline blouse showing my new design in adjusted position.

Figure 2 is a rear elevational view of same, and

Figure 3 is a flat plan view thereof showing the basic contour of the design.

The blouse shown in Figure 1 is formed by being drawn over the head and pulled down to form generally horizontal tucks at the bosom, and the edges of the cuff are turned back to form a col-

lar which is held in place by the elasticity of the material and a pin at the neckline.

I claim:

The ornamental design for a knitted slipover adjustable neckline blouse, substantially as shown and described.

JOSEPHINE HAYWARD.
